UNITED STATES PATENT OFFICE.

BENJAMIN MCINNERNEY, OF COUNCIL BLUFFS, IOWA, ASSIGNOR TO WESTINGHOUSE ELECTRIC & MANUFACTURING COMPANY, A CORPORATION OF PENNSYLVANIA.

ELECTROMAGNET.

1,365,332.

Specification of Letters Patent. Patented Jan. 11, 1921.

Application filed March 28, 1917. Serial No. 157,923.

To all whom it may concern:

Be it known that I, BENJAMIN MCINNERNEY, a citizen of the United States, and a resident of Council Bluffs, in the county of 5 Pottawattamie and State of Iowa, have invented a new and useful Improvement in Electromagnets, of which the following is a specification.

My invention relates to electromagnets, 10 and it has for its object to provide a simple and effective arrangement for preventing or diminishing the shocks incident to the engagement of movable armature members with coacting stationary parts.

15 It is well known that the pull of an electromagnet is of minimum value when the armature member is in its open position and the air gap which separates the core member from the armature member is of maximum width. The pull increases rapidly as the armature member moves toward the core member and the width of the air gap is diminished. The result is to cause the armature member to engage the stationary part with which it coacts with a considerable shock or impact, since the force exerted upon it is a maximum at the instant of engagement.

20 The noises incident to the engagement of the rapidly moving parts are particularly noticeable in connection with relatively large electromagnets where the moving parts have considerable weight. When electromagnets are employed in connection with 25 elevators and hoists and are mounted at the tops of the shafts or in overhead structures, the noises are particularly objectionable.

It is possible to partially avoid the undesirable features mentioned above by the 30 employment of dashpots or by submerging the electromagnets in oil. These arrangements are, however, unsatisfactory for the reason that it is necessary to make occasional adjustments of dashpots in order that 35 they may be effective. It is necessary, also, that tanks for surrounding oil-submerged electromagnets be maintained in such condition as to prevent leakage of the oil and that the supply of oil be replenished at intervals.

40 It has been found, in practice, that the attendants of elevators and similar machines neglect their duties in these regards and the devices become practically useless.

The arrangement which comprises the 45 subject matter of the present application re-

quires no adjustment or attention after it is installed. A segment of conducting material, such, for example, as iron, steel or copper, is operatively connected to the movable armature member of an electromagnet and 60 is arranged to move through a path that is immediately adjacent to the armature member and core member during the closing movement of the armature member. The damping segment, as it may be termed, 65 passes through a portion of the magnetic field of the electromagnet and the eddy currents, which are set up in the segment, cause a retarding effect that is proportional to the strength of the field of the electromagnet 70 and to the speed at which the segment is actuated.

The retarding force exerted by the damping segment increases as the armature member approaches its closed position since an 75 increased portion of the segment is adjacent to the air gap between the members of the electromagnet. This characteristic of the operation of the retarding device is desirable since the retarding force is of maximum degree when the force actuating the core member to its closed position is also at a maximum.

While my invention is adapted to be employed in connection with electromagnets 80 of the general character illustrated in the drawing, it is preferably employed in connection with electromagnets such as that shown and described in my Patent No. 1,238,313, granted August 28, 1917, and assigned to the Westinghouse Electric & Manufacturing Co.

85 In the accompanying drawing, Figure 1 is an end view, in elevation, of an electromagnet constructed in accordance with my 90 invention. Fig. 2 is a side view, in elevation, of a portion of the electromagnet shown in Fig. 1.

An electromagnet comprises a stationary magnetizable member 1 which may have any 100 desired number of polar projections. The core member 1 may be provided with any suitable number of coils in accordance with the character of the source of energy, a single coil 2 being shown.

An armature member 3 is pivotally mounted at 4 by means of a pair of levers 5, only one of which appears on the drawing. The levers 5 are provided with suitable holes 6 by means of which they may be connected to 110

any suitable mechanisms, such, for example, as brakes for elevators.

A member 7, which may be termed a damping segment, is pivotally mounted at 8 for movement through a path immediately adjacent to the corresponding ends of the core member 1 and the armature member 3. The member 7, which is of conducting material, is operatively connected to the armature member 3 by means of a link 9. If such arrangement is necessary or desirable, a similar member 7 may be mounted at the other end of the electromagnet.

The damping segment 7 is preferably maintained in engagement with the core member 1 in any desired manner, as by means of a spring 10. This preferred arrangement serves a double purpose; first, the damping segment is thereby prevented from rattling after it wears loose and secondly, if the segment is made of steel, it has been found that a greater damping effect is thereby obtained, probably due to friction between the segment and the core member 1.

It may be assumed that the armature member 3 occupies its open position and the damping segment 7 occupies its corresponding position which is indicated by dot-and-dash lines, Fig. 1. It will be noted that, when the damping segment 7 occupies its normal position, substantially no part of the air gap between the armature member 3 and the core member 1 is bridged by it.

It may be assumed, further, that the circuit of the coil 2 has been completed and the latter energizes the magnetic circuits of the core member 1. The armature member 3 is drawn downwardly with a constantly increasing pull as the reluctance of the magnetic circuit is diminished by the decrease in the width of the air gap.

Simultaneously with the movement of the armature member 3, the damping segment 7 is actuated in a clockwise direction about its point of pivotal support to bridge an increasing portion of the air gap between the end of the armature member 3 and the corresponding portion of the core member 1. The damping segment 7 traverses part of the magnetic circuit of the electromagnet and eddy currents are induced which cause the segment to operate as a damper to retard the closing movement of the armature.

The retarding force increases by reason of the fact that a larger portion of its surface bridges the air gap, and, in addition, the speed of the armature member 3 tends to increase as it approaches the core member 1. The result is to effectively retard the movement of the armature member 3 and thereby prevent the noise that is ordinarily incident to the striking of the pole faces of the core member.

It will be noted that an arrangement constructed in accordance with my invention is

much more simple and economical than the methods of the prior art previously discussed. After the damping device is installed, neither attention nor adjustment is necessary. The device operates automatically and with a force that varies in accordance with the operating conditions of the electromagnet in connection with which it is employed. My invention is particularly adapted for use in connection with electromagnets embodied in controlling mechanisms such, for example, as elevators in hospitals, hotels and apartment houses where unusual noises are particularly undesirable.

I claim as my invention:

1. In an electromagnet, the combination with a core member and an armature member coacting therewith, of means coöperating with the magnetic field of said electromagnet for retarding the movement of said armature member with an increasing effect as the armature is actuated to its closed position.

2. In an electromagnet, the combination with a core member and an armature member coacting therewith, of means for retarding the movement of said armature member with a varying effect, said means comprising a movable member of conducting material for shunting a portion of the magnetic flux of said electromagnet.

3. In an electromagnet, the combination with a core member and an armature member coacting therewith, of means comprising a movable member of conducting material operatively connected to said armature member and coöperating with the magnetic field of said electromagnet, for retarding the movement of the latter member to its closed position.

4. In an electromagnet, the combination with a stationary portion and a movable portion coacting therewith and normally separated therefrom by a gap, of means for retarding the closing movement of said movable portion, said means comprising a movable conducting member adjacent to said gap and coöperating with the magnetic flux of said electromagnet.

5. In an electromagnet, the combination with a stationary portion and a movable portion coacting therewith, of means for retarding the closing movement of said movable portion, said means comprising a movable member of conducting material adjacent to each of said portions and coöperating with the magnetic flux of said electromagnet and operatively connected to the movable portion.

6. In an electromagnet, the combination with a stationary portion and a movable portion coacting therewith, of means for retarding the closing movement of said movable conducting portion, said means

- comprising a movable member adjacent to each of said portions and coöperating with the magnetic flux of said electromagnet and arranged to present an increasing surface to 5 the gap between them as the movable portion approaches its closed position.
7. The combination with an electromagnet having a pair of relatively movable members normally separated by a gap, of 10 means coöperating with the magnetic flux of said electromagnet for creating eddy currents in the neighborhood of said gap for retarding the relative movement of said members.
- 15 8. The combination with an electromagnet having a stationary core member and a movable armature member, of a conducting member and means for moving said conducting member in the magnetic field of 20 said electromagnet during the closing movement of said armature member to create eddy currents for retarding said movement.
9. The combination with an electromagnet comprising a stationary core member
- and an armature member pivotally mounted 25 thereon, of a conducting segment pivotally mounted upon said stationary member for movement through the magnetic field of said electromagnet, and a link connecting said armature member to said conducting 30 segment whereby movement of said armature member is controlled by said segment.
10. The combination with an electromagnet having a stationary core member and a movable armature member normally separated therefrom by a gap, of a conducting member normally distant from said gap and movable into the neighborhood of said gap and means for so moving said conducting member as to increase the portion of said 35 40 conducting member in the neighborhood of said gap in accordance with a decrease in the size of said gap.

In testimony whereof, I have hereunto subscribed my name this 19th day of March, 45 1917.

BENJAMIN McINNERNEY.
